CLAIM

The ornamental design for a boiler control housing cover, as shown and described.

DESCRIPTION

FIG. 1 illustrates a front, top, and right side perspective view of a boiler control housing cover according to one exemplary aspect of the present invention.

FIG. 2 illustrates a back, bottom, and left side perspective view of the boiler control housing cover of FIG. 1.

FIG. 3 illustrates a front elevation view of the boiler control housing cover of FIG. 1.

FIG. 4 illustrates a back elevation view of the boiler control housing cover of FIG. 1.

FIG. 5 illustrates a right side elevation view of the boiler control housing cover of FIG. 1.

FIG. 6 illustrates a left side elevation view of the boiler control housing cover of FIG. 1.

FIG. 7 illustrates a top side elevation view of the boiler control housing cover of FIG. 1; and,

FIG. 8 illustrates a bottom side elevation view of the boiler control housing cover of FIG. 1.

The broken line portion of the figures is included to show the unclaimed subject matter only and forms no part of the claimed design.
